UNITED STATES PATENT OFFICE

95,253

DESIGN FOR A RUBBER DIAPER

Kurt Heitler, New York, N. Y.

Application December 19, 1934, Serial No. 54,491

Term of patent 14 years

To all whom it may concern:

Be it known that I, Kurt Heitler, a citizen of the United States, and a resident of the city of New York (Borough of Manhattan), in the county of New York and State of New York, have invented a new, original, and ornamental Design for Rubber Diapers, of which the following is a specification, reference being had to the accompanying drawing, forming part thereof, in which

Figure 1 is an elevation of a rubber diaper slightly in perspective, the same showing my new design, and

Figure 2 is an edge view of the diaper shown

in Figure 1, the parts being in approximately the position when the diaper is in use.

The dominant features of my invention consist in the cross-shaped body when viewed from the front and an ornamental thread formation at the waist-band and leg openings, together with the ruffled trimming near the waist-line and leg openings forming an ornamental frame.

I claim:

The ornamental design for a rubber diaper, substantially as shown and described.

KURT HEITLER.
